Primary Examiner—Ted Shooman*Assistant Examiner*—Carol Rademaker(74) *Attorney, Agent, or Firm*—Drinker Biddle & Reath LLP**CLAIM**

The ornamental design of a bottle, as shown and described.

DESCRIPTION

FIG. 1 is a front isometric view as seen from above of a bottle of our new design.

FIG. 2 is a front elevation of the bottle of FIG. 1; the rear elevation being a mirror image.

FIG. 3 is a side elevation of the bottle of FIG. 1, the opposite side elevation being a mirror image.

FIG. 4 is a top plan view of the bottle of FIG. 1.

FIG. 5 is a bottom plan view of the bottle of FIG. 1.

FIG. 6 is a front isometric view as seen from above of a second embodiment of a bottle of our new design.

FIG. 7 is a front elevation of the bottle of FIG. 6; the rear elevation being a mirror image.

FIG. 8 is a side elevation of the bottle of FIG. 6, the opposite side elevation being a mirror image.

FIG. 9 is a top plan view of the bottle of FIG. 6; and,

FIG. 10 is a bottom plan view of the bottle of FIG. 6.

UNITED STATES PATENT AND TRADEMARK OFFICE
CERTIFICATE OF CORRECTION

PATENT NO. : Des. 480,004 S
DATED : September 30, 2003
INVENTOR(S) : Beachum et al.

Page 1 of 1

It is certified that error appears in the above-identified patent and that said Letters Patent is hereby corrected as shown below:

Title page.

Item [75], Inventor, please change "**Nicholas Latorre**" to -- **Nickolas Latorre** --.

Signed and Sealed this

Twenty-second Day of November, 2005

A handwritten signature in black ink, appearing to read "Jon W. Dudas". The signature is written in a cursive style with a large, stylized 'J' at the beginning.

JON W. DUDAS
Director of the United States Patent and Trademark Office
